Wesley G. Barr
ATTORNEY

UNITED STATES PATENT OFFICE

REINHOLD RÜDENBERG, OF BERLIN-GRUNEWALD, GERMANY, ASSIGNOR TO WESTINGHOUSE ELECTRIC & MANUFACTURING COMPANY, A CORPORATION OF PENNSYLVANIA

CIRCUIT INTERRUPTER

Application filed April 5, 1928, Serial No. 287,743, and in Germany January 28, 1927.

My invention relates to circuit interrupters and more particularly to contact members therefor.

One object of my invention is to provide 5 contact members for a circuit interrupter that shall decrease the time of interrupting the arc established by the contact members upon the operation of the circuit interrupter.

Another object of my invention is to increase 10 the speed of arc interruption by providing contact members that shall move transversely with respect to the arc to provide new and cool surfaces therefor.

A further object of my invention is to 15 provide contact members for a circuit interrupter that shall be rotated during the time of arc interruption.

The present trend in the design of circuit 20 interrupters is toward a structure that is capable of decreasing the time to completely interrupt the arc. Many structures have been provided to accomplish this end, the most familiar employed at the present time is one that produces an increased acceleration 25 of the moving members, one that provides a magnet and an arc extinguishing chamber for dissipating the arc, or one that employs a liquid director to project a cool stream of liquid across the arc path to there- 30 by cool and quench it.

My present invention relates to a new and 35 novel means in order to effect, as quickly as possible, an interruption of the arc in a circuit interrupter after the disengagement of the contact members. The present invention is based upon the fact that an arc will be extinguished relatively easily if its base, that is to say the point of the contact members from which it extends, is cooled. 40 This cooling prevents overheating of the parts of the contact members and thereby prevents an omission of electrons which would help in maintaining the arc.

In accordance with the present invention, 45 the contact members of the circuit interrupter are so designed and arranged that those points at which the arc starts upon separation thereat will change their position. The special embodiment herein shown 50 accomplishes this result by providing me-

chanical means for rotating the contact members.

My invention will best be understood by referring to the drawing in which the single figure discloses a particular embodiment of 55 my invention in elevation with the tank portion of the circuit interrupter cut away disclosing the contact members.

My invention comprises, in general, a circuit interrupter 1 having a tank 2 that contains 6 a liquid 3 in which the contact members 4 are immersed and which will now be described in detail.

The tank 2 contains a cover 5 that supports the terminal bushings 6 and 7. The lower portion of the bushings 6 and 7 extend 65 into the liquid 3 and support the rotatable contact members 4 on their extreme ends by pins 8. A bridging member 9 is supported by the lift rod 11 that passes through the cover 5 through the aperture 12 and is actuated by the operating mechanism (not shown). Each end of the bridging member 9 contains a pin 13 that supports a rotatable contact member 4 adjacent to the rotatable 70 contact member 4 supported by bushings 6 and 7. Sliding contacts 14 are provided, adjacent to each of the rollers, above-described. The current to the rotatable contact members 4 will pass through these sliding contacts and prevent arcing taking place at the pins 8 which otherwise would produce a pitting thereat and increase the resistance to rotation.

Ratchet bars 15 are provided on the bridging member to engage pinions 16 on the rotatable contact member 4 to produce rotation in the said contact 4 upon the movement of the bridging member 9. Similarly, rotation of the contact member 4 supported on the bridging member 9 is obtained by its movement with the said bridging member. This movement is produced by a ratchet 17 that is fixed to the bushings 6 and 7 and engages a pinion 18 on the contact member 4. 95 The rotation thus produced will be in opposite directions to the rotation of the contact member 4 adjacent thereto, that is to say one contact member will be rotated in a clockwise direction while the adjacent contact mem- 100

ber will rotate in a counter-clockwise direction. By so rotating the contact members, the termini of the arc will be displaced in opposite vertical directions which will tend to increase the length of the arc.

It will thus be seen that I provide contact members for a circuit interrupter that move transversely with respect to the arc to provide new and cool surfaces therefor and thereby prevent the emission of ions that would sustain the arc and prevent it from being easily extinguished. The single figure of the drawing discloses a particular embodiment of my invention, and I do not wish to be limited to the special structure shown in the figure, or to oil immersed circuit interrupters as the principle of my invention may be applied to contact members of any circuit interrupting mechanism in which the contact may be moved by any means relative to the arc.

It is, therefore, to be understood that such changes in the form, arrangement, and connection of the component parts of my invention may be made as shall fall within the scope of the appended claims.

I claim as my invention:—

1. The combination in a circuit interrupter having separable contact members, of a movable member for supporting one of the contact members, and means actuated by the movement of the said movable member adapted to produce a movement of rotation in all of the contact members.
2. The combination in a liquid immersed circuit interrupter having a pair of leads extending into the liquid shunted at their lower end by a bridging member that is supported on an operating member, of rotatable contact members supported on the ends of the said leads and the bridging members respectively, and means associating with the bridging members, the leads and the contact members and adapted to rotate the last said members by the movement of the operating member.
3. The combination in a liquid immersed circuit interrupter having a pair of leads extending into the liquid shunted at their lower ends by a bridging member that is supported on an operating member that is releasable to permit the bridging member to move, of rotatable contact members supported on the ends of the said leads and the bridging members respectively, and means associating with the bridging members, the leads and the contact members adapted to rotate the last said members by the movement of separation of the bridging member.
4. The combination in a liquid immersed circuit interrupter having a pair of leads and a bridging member submerged in the liquid, of rotatable contact members associated with the leads and the bridging member, and means cooperating with the said contact members adapted to procure their rotation by the

movement of separation of the bridging member.

5. In combination with a container and a liquid therein, a plurality of leads and bridging members submerged in said liquid, of a plurality of rotatable contact members associated with the plurality of leads and bridging members completing a plurality of circuits thereby, and means cooperating with the leads, the bridging members and the contact members adapted to rotate the last said members by means of the movement of the bridging members.

6. In a circuit interrupter, the combination with a plurality of contact members mounted on stationary and movable members, means associated with the contact members adapted to procure their rotation by the movement of the movable member when the said contact members separate.

In testimony whereof, I have hereunto subscribed my name this 22nd day of February 1928.

REINHOLD RÜDENBERG.
